UNITED STATES PATENT OFFICE.

FRANK A. GURLEY, OF MERIDIAN, MISSISSIPPI.

DESIGN FOR A BACK-BAND HOOK.

SPECIFICATION forming part of Design No. 28,349, dated March 8, 1898.

Application filed January 31, 1898. Serial No. 668,678. Term of patent 14 years.

To all whom it may concern:

Be it known that I, FRANK A. GURLEY, a citizen of the United States, residing at Meridian, in the county of Lauderdale and State of Mississippi, have invented a new and original Design for a Back-Band Hook, of which the following is a specification.

This invention relates to a new and original design for a back-band hook; and it has for its object to provide a design of this character that shall be both useful and ornamental.

The leading feature of the design resides in a base-plate of a circular form, having in its rear face a circular opening, a concavo-convex hood portion arranged at the front side and overhanging a portion of said circular opening, the arched edge of said hood portion lying obliquely to the plane of the base-plate, said base-plate being further provided at one edge with a U-shaped hook portion having an inturned extremity projected through the front opening bounded by the edge of said hood portion.

In the drawings, Figure 1 is a front view of a back-band hook embodying the herein-described design. Fig. 2 is a rear view thereof. Fig. 3 is a cross-sectional view on the line 3 3 of Fig. 2.

Referring to the accompanying drawings, the numeral 1 designates a base-plate of a 30 circular form, having a triangular group of offstanding rounded peripheral ears 2, provided therein with circular openings 3. The said base-plate is further provided with a circular opening 4, piercing the rear side thereof, and at its front side with a concavo-convex hood portion 5, overhanging a portion of said circular opening and having its arched edge lying obliquely to the plane of the base-plate. The said base-plate is further provided at one 40 edge with a U-shaped hook portion 6, having an outer straight arm extended through the front opening bounded by the edge of said hood portion and provided at its terminal with an inturned lug projection 7. 45

What is claimed is—

The design for a back-band hook, herein shown and described.

In testimony that I claim the foregoing as my own I have hereto affixed my signature in 50 the presence of two witnesses.

FRANK A. GURLEY.
